UNITED STATES PATENT OFFICE

PASCHAL L. BOTTOMS, OF AMARILLO, TEXAS

SCAFFOLD

Application filed December 12, 1928. Serial No. 325,522.

This invention relates to improvements in scaffolds adapted to be used by masons, painters and the like, and the primary object of the invention is to generally simplify and improve the form and type of scaffold disclosed in my U. S. Letters Patent No. 1,673,862, dated June 19, 1928.

More particular objects of the present invention are to improve and render more durable, efficient and safe the hoisting devices by means of which the scaffold platform is suspended from the top of the building, and to provide means for promoting the ease of raising and lowering the platform while steady-
ing the same against swaying movements.

Other objects will become apparent as the nature of the invention is better understood, and the same consists in the novel form, combination and arrangement of parts herein-
after more fully described, shown in the accompanying drawings, and claimed.

In the drawings, wherein like reference characters indicate corresponding parts throughout the several views;

25 Figure 1 is a diagrammatic side elevational view of the framework of a building, with a scaffold constructed in accordance with the present invention mounted thereon.

Figure 2 is a side elevational view, partly broken away, of one of the hoisting devices employed in the scaffold shown in Figure 1.

Figure 3 is a top plan view of the device shown in Figure 2.

Figure 4 is a fragmentary vertical section taken on line 4—4 of Figure 3.

Figure 5 is an enlarged detail section on line 5—5 of Figure 3; and

Figure 6 is an enlarged fragmentary horizontal section on line 6—6 of Figure 2.

40 Referring more in detail to the drawings, 5 indicates the framework of a building, and suspended at each end from the top of the building by means of a hoisting device is a scaffold platform 6.

45 As the hoisting devices are alike, descrip-

tion of one will suffice for both. As shown, each hoisting device embodies a frame composed of a pair of channel beams 7 rigidly connected in spaced parallel relation by means of bolts 8 and 8a passing through the opposite end portions of said beams, and spacing sleeves 9 and 9a fitted on said bolts between said beams. This frame is suitably secured to the top of the building so as to project a distance beyond the front of the latter, and secured at their lower ends by the bolts 8a to the outer sides of the inboard ends of the beams 7 are spaced upright supporting plates or castings 10 having inwardly projecting horizontal flanges 11 intermediate their top and bottom edges flatly seated on the beams 7. The supporting plates 10 have integral reinforcing ribs —R— on the outer faces thereof and are shaped to provide inclined upper edges adjacent which are 65 formed a series of bearings —B—, respectively arranged at different elevations. The shafts —S— of winding drums 12 and 13 are journaled in the highest and lowest ones of the bearings —B— respectively, and the ends 70 of these drums have pairs of similar spur gears 14 and 15 engaged by pawls 16 and 17 whereby the drums may be freely turned in one direction but are prevented from turning in the opposite direction unless the pawls 75 are manually released. As shown, the pawls are rigid with transverse horizontal rock shafts 16a and 17a journaled in extensions 18 and 19 of the supporting plates 10. Weighted levers —L— are fixed on the projecting ends of the rock shafts 16a and 17a to normally yieldingly engage the pawls 16 and 17 with the gears 14 and 15 and to facilitate manual release of such pawls.

Slidably and rotatably mounted in the intermediate bearings —B— of the supporting plates 10 is a shaft 21 having projecting ends on which are secured operating cranks 22 and on which are secured elongated or relatively wide spur pinions 23 arranged be- 90

tween and adapted to simultaneously mesh with the gears 14 and 15. The gears 14 and 15 are laterally offset with respect to each other as shown in Figure 3. The pinions 23 are spaced apart, however, so as to leave spaces between the same and the supporting plates 10, whereby the shaft 21 may be slid laterally of the beams 7 to disengage the pinions 23 from the gears 14 while remaining engaged with the gears 15, or to disengage them from the gears 15 while remaining engaged with the gears 14. In this way, either winding drum may be disconnected or freed from the operating shaft 21 and the other drum for independent actuation to enable any slack to be taken up in either of the cables 24 or 25 for transversely leveling the scaffold platform 6 preparatory to raising the latter. The cable 24 is attached to drum 12 and passes outwardly over a guide pulley 26 carried by a shaft 27 journaled in the outer ends of the beams 7, the lower ends of the cable 24 being attached to the outer side of platform 6. In a like manner, the cable 25 is attached to the drum 13 and the inner side of the platform 6 the said cable passing over a guide pulley 28 carried by a shaft 29 journaled in the beams 7 inwardly of the shaft 27. It is thus apparent that by turning shaft 21 with the pinions 23 engaging the gears 14 and 15, both drums may be turned at the same speed to wind the cables 24 and 25 thereon and raise the end of the scaffold platform 6 while preserving the transverse level of the latter. A corresponding operation of the other hoisting device for the other end of the platform will result in raising the latter while preserving its level longitudinally.

In order to prevent accidental shifting of the shaft 21 transversely of the frame when the pinions 23 are in mesh with the gears 14 and 15, I provide chock members 30 which are pivoted to the inner sides of the supporting plates 10 and are adapted to be swung to or from position between the pinions 23 and the supporting plates 10, the chock members 30 being shaped to fit over shaft 21 as shown in Figure 5 and having handles 32.

Journaled in the supporting plates 10 below the operating shaft 21 is a transverse rock shaft 40 having a pawl 41 rigid therewith and arranged to engage a pinion 53 secured on and arranged centrally of operating shaft 21, so as to prevent said operating shaft from turning in one direction while permitting free turning thereof in the opposite direction. In this way, the pawls 16 and 17 are supplemented by the pawl 41 to provide an additional safeguard against accidental retrograde turning of the drums 12 and 13 and unwinding of the cables 24 and 25 therefrom. Weighted levers 42 are fixed on the projecting ends of the rock shaft 40 to normally yieldingly engage the pawl 41 with the pinion 53 and to facilitate manual

rotation of shaft 40 and release of said pawl.

A further transverse rock shaft 43 is journaled in the supporting plates 10 below the shaft 40 and has foot levers 44 fixed on its projecting ends. Rigid with shaft 43 is an arm 45 to which is connected one end of a brake band or strap 46 that passes over a brake drum 47 secured on the operating shaft 21. The other end of the brake band or strap 46 is provided with a loop loosely engaged with shaft 40 so as to be anchored to the latter without interfering with turning thereof. Depression of either foot lever 44 will cause application of the brake band 46 to control the rotation of drums 12 and 13 for preventing the platform 6 from lowering at an excessive rate of speed when the pawls 16, 17 and 41 are released. 75

Pairs of opposed vertical flanges 48 are rigid with and project inwardly from the supporting plates 10 above the horizontal flanges 11, and plates 49 are bolted to and connect these pairs of flanges 48 to rigidly connect such supporting plates and prevent spreading of the upper portions thereof. 85

As shown in Figures 1 and 2, the platform 6 embodies boards laid across end transverse beams 33 and held down by cross bars 34 bolted to said beams and engaged at their ends beneath the eyes on the upper ends of eye-bolts 35 anchored in the said beams. The cables 24 and 25 are connected to the eye-bolts 35 and the boards of platform 6 are arranged between the latter as shown in Figure 2. Attached to the inner ends of the beams 33 are brackets or mounts 50 in which are journaled wheels 51 adapted to engage and ride on the outer face of the wall of the building so as to promote the ease of raising and lowering the platform, and to steady the 100 same against swaying movements.

In operating the device to lift the platform, the cranks 22 are turned to rotate the drums 12 and 13 at the same rate of speed and wind up the two cables at the same rate 105 so that the platform will not be tilted.

Minor changes may be made without departing from the spirit and scope of the invention as claimed.

What I claim as new is:

1. In a scaffold, a support embodying an outrigger frame, a pair of upright supporting plates attached to and projecting upwardly from the inboard end of said frame and having means to facilitate journaling of winding drums thereon, said supporting plates also having pairs of opposed inwardly projecting vertical flanges on the upper portions thereof, and a transverse plate rigidly secured to and connecting each pair of vertical flanges to prevent relative spreading of said supporting plates. 115

2. In a scaffold, an outrigger frame embodying a pair of channel beams rigidly connected in spaced parallel relation, a pair of 120

upright supporting plates rigidly secured to and projecting upwardly from the inboard ends of said beams, said supporting plates having inwardly projecting horizontal flanges seated on said beams and pairs of opposed inwardly projecting vertical flanges above said horizontal flanges, transverse plates rigidly secured to and connecting said pairs of vertical flanges, and means to facilitate journalling of winding drums in the upper portions of said supporting plates.

3. In a scaffold, an outrigger frame embodying a pair of channel beams rigidly connected in spaced parallel relation, a pair of upright supporting plates rigidly secured to and projecting upwardly from the inboard ends of said beams, said supporting plates having inwardly projecting horizontal flanges seated on said beams and pairs of opposed inwardly projecting vertical flanges above said horizontal flanges, transverse plates rigidly secured to and connecting said pairs of vertical flanges, and means to facilitate journalling of winding drums and of an operating shaft for said drums at different levels in the upper portions of said supporting plates.

4. In a scaffold having a platform, a support, a pair of winding drums mounted on said support and disposed in laterally offset relation, spur gears on the ends of said drums, an operating shaft journaled between the drums and having pinions adapted to simultaneously mesh with the gears of both drums, said shaft being slidable transversely of the support to selectively disengage the pinions from the gears of either drum, cables attached to the drums and adapted to be attached to the platform at the inner and outer sides of the latter, in combination with a rock shaft journaled in said support parallel with and below said operating shaft and having its ends projecting at opposite sides of said support, foot levers secured on said projecting ends of the rock shaft, an elongated brake drum carried by said operating shaft, an arm rigid with said rock shaft, and a brake band operatively associated with said brake drum in either position to which the operating shaft may be slid transversely of the support, said brake band being operatively connected to said arm for being applied upon depression of said foot levers.

5. In a scaffold having a platform, a support, a pair of winding drums mounted on said support and disposed in laterally offset relation, spur gears on the ends of said drums, an operating shaft journaled between the drums and having pinions adapted to simultaneously mesh with the gears of both drums, said shaft being slidable transversely of the support to selectively disengage the pinions from the gears of either drum, cables attached to the drums and adapted to be attached to the platform at the inner and outer

sides of the latter, in combination with rock shafts journaled adjacent the operating shaft and adjacent said drums transversely of the support, pawls carried by said rock shafts adjacent the opposite ends of the latter and arranged to engage the pinions and the spur gears, and weighted levers on the opposite ends of said rock shafts to normally yieldingly engage the pawls with said pinions and gears.

In testimony whereof I affix my signature.
PASCHAL L. BOTTOMS.
